UNITED STATES PATENT OFFICE

ALFRED W. SCHULTZ, OF WATERLOO, IOWA, ASSIGNOR TO THE ZEIDLER CONCRETE PRODUCTS MACHINERY COMPANY, OF WATERLOO, IOWA

TITLE-MAKING MACHINE

Application filed June 28, 1928. Serial No. 288,871.

My invention relates to improvements in tile making machines, and the object of my improvement is to perfect the construction of that class of machines which are adapted to operate in the forming of hollow cement or concrete tile sections, by combining with the mold and interior former-head thereof, a device removably and movably seated within the mold centrally above the former-head to cooperate therewith in the directing of the plastic material toward the inner wall of the mold there to be shaped by the former-head.

This object I have accomplished by the means which are hereinafter described and claimed, and which are illustrated in the accompanying drawings, in which the figure is a conventional central vertical section of a machine of the class described, including the new cooperating elements of my invention, the full and the dotted lines denoting opposite positions of said new cooperating elements relative to the mold and the included former-head of the machine.

My invention is not restricted to the precise construction and arrangement of parts herein shown and described, nor to the various details thereof, as the same may be modified or rearranged in various particulars without departing from the spirit and scope of my invention, one practical embodiment of which has been herein illustrated and described without attempting to show all of the various forms and modifications in which my invention might be embodied.

The numeral 9 conventionally represents a hollow cylindrical mold within which may be formed a hollow cylindrical tile of suitable plastic material. However, the mold may be of any desired configuration without departing from the invention. This mold 9 may be seated concentrically within a raised annulus 4 being part of a base-plate 3 upon whose interiorly projecting annular rim the mold and the hollow tile to be formed therein may be supported around a central opening 7 through which may move vertically a cylindrical former-head 10 concentric with said mold.

The base-plate 3 may be removably sup-

ported upon a fixed support 1 having a wider opening 2 below and concentric with the said opening 7. A top-plate 5, of similar shape to the base-plate 3, has its depending central annulus 6 fitted over the top edge of the mold 9, and the plate 5 has a concentric opening 8 of less diameter than said mold so that the plate serves as an end closure for the top of the mold and therearound to shape the upper edge of a tile to be formed therein.

Upon the top-plate 5 is supported a hollow cylindrical body 11, whose bottom part has a wide diameter opening, and a downwardly directed hollow conical frustum 12 is fitted into the hollow of the body 11 to serve as a hopper or funnel to receive and deliver downwardly through the opening 8 a charge of the plastic cement sufficient for one tile. This charge of cement or concrete is denoted by the numeral 28 and is shown as delivered into the mold above and around the former-head 10 which is positioned partly within the mold as in shaping a tile therein between itself and the inner wall of the mold, it being understood that said former-head in said operation rotates while being simultaneously propelled in a right line vertically centrally through the mold, as is usual in this art.

As in practice it has been found that the plastic material when delivered into the mold often accumulates upon the top of the former-head and is not properly deflected radially outward toward the inner wall of the mold and thence downwardly between the mold and the former-head, I have supplied new and useful means for deflecting such material in the desired directions as stated.

This means consists of a body 13 positioned to be moved into or out of the mold concentrically, this body 13 being secured upon the lower end of a cylindrical shank 14 of less diameter, the body 13 being preferably shaped as apposed oppositely directed conical frusta separated by a narrow cylindrical band. However, this body or deflector 13 may be otherwise shaped without departing from the invention.

The numerals 21 and 23 denote like vertical loops depending and fixed on opposite sides of the box 11 from and fastened to vertically movable supports 26 above. Projecting outwardly from the loop hanger 23 is a short horizontal arm 25 fixed rigidly thereon, and an inwardly projecting arm or lever 17 has its outer end pivoted to the outer end of the arm 25 at 24. The arm 17 is curved upwardly at 19 and has a straight terminal handle part 20 which is without the loop hanger 21, as the curved part 19 traverses the vertical opening of the hanger and is stopped therein by the cross-bar 22 thereof. A side-bar 18 may be set off from one face of the arm 17 over the shank 14 and secured thereto by bolts. Short links 15 are pivotally connected between the upper end of the shank 14 and the arm parts 17 and 18, whereby the shank 14 and the deflector head 13 are suspended concentrically relative to the mold 9, to move into or out of the mold when the arm 17 is swung downwardly or upwardly as the case may be. The dotted lines indicate the positions of the arm 17 and the deflector head 13-14 when raised out of the mold, in which position the arm may be sprung enough to permit it to enter and be held in its upper position by a hook 27 depending from the upper supporting body 26.

When a charge of the plastic cement is deposited into the funnel hopper 12 and delivered thence into the mold 9, the upper frustum of the head 13 deflects the material toward the inner wall of the mold, to fall between the rotating former-head 10 and the mold, and as the former-head 10 ascends through the mold together with the deflector-head 13 any material which may have accumulated between the former-head and the lower frustum of the deflector head 13 is squeezed therebetween and driven outwardly toward and into the region to be occupied by the fully formed tile. The upwardly moving former-head with any interposed material pushes up the deflector-head 13 until the latter is cleared from the mold and the former-head has finished its troweling of the inside of the tile. The operator may then swing upwardly the arm 17 to engage it with the hook 27. The depending looped hangers 21 and 23 may then be shifted upwardly to lift the hopper 11 and top-plate 5 away from the mold 9, which may be removed, and replaced by an empty mold.

Having described my invention, what I claim as new, and desire to secure by Letters Patent, is:

In a tile machine, an open end hollow mold, a former-head movable into and out of the mold through its open lower end, a hopper seated upon said mold to deliver thereto, means connected to said hopper to move it to and from said mold, a deflec-

tor-head within said mold and of less width than a tile to be formed therein, and positioned above the former-head, an operating arm linked to said deflector-head to shift the latter into and out of said mold, and means for limiting the scope of movement of said deflector-head and arm, the deflector-head being adapted to deflect entering material to the interspace of the mold and former-head and to be moved upwardly with the upward progress of the former-head by pressure of the latter upon intervening material.

In testimony whereof I affix my signature.

ALFRED W. SCHULTZ.
